E. JACOBSEN.
FILE FOR CORRESPONDENCE AND THE LIKE.
APPLICATION FILED JAN. 16, 1918.

1,273,862.

Patented July 30, 1918.

Inventor:
Ernest Jacobsen
By Paul Riney, Jr.
Attorney.

UNITED STATES PATENT OFFICE.

ERNEST JACOBSEN, OF MELBOURNE, VICTORIA, AUSTRALIA.

FILE FOR CORRESPONDENCE AND THE LIKE.

1,273,862.

Specification of Letters Patent. Patented July 30, 1918.

Application filed January 16, 1918. Serial No. 212,038.

To all whom it may concern:

Be it known that I, ERNEST JACOBSEN, a subject of the King of Great Britain and Ireland, and a resident of the city of Melbourne, in the county of Bourke, State of Victoria, Commonwealth of Australia, whose post-office address is Church Lane, 375 Collins street, in the said city of Melbourne, have invented certain new and useful Improvements Relating to Files for Correspondence and the like, of which the following is a specification.

The object of the invention is to provide a cheap and effective file for expeditiously binding correspondence and other papers.

By the invention correspondence and the like may be rapidly threaded onto a binding medium and effectively retained in position by a locking member, whereby the ends of the binding medium are prevented from slackening, or becoming loose leading to the damage of the papers. At the same time correspondence may be rapidly detached from the file and replaced as desired.

The invention may be applied to a cover of the class commonly used in filing systems, or it may be applied to a box or other suitable form of file. For convenience the invention will be hereinafter described and illustrated as applied to a file of the former class, but it is to be understood that it is not limited to use therewith.

But in order that this invention may be better understood reference will now be made to the accompanying drawing which is to be taken as part of this specification and read herewith.

Figure 1 is a perspective view of a file embodying the present invention.

Fig. 2 is a detail side view on an enlarged scale showing in full lines the pivoted locking plate closed or in its locking position, the ends of the binding medium being shown locked between the locking plate and the metal reinforcement. In broken lines the locking plate is shown partly open or disengaged from the metal reinforcement. Parts are broken away for convenience of illustration.

Fig. 3 is a sectional perspective view showing clearly the metal reinforcement attached to one of the leaves or wings of the cover. Parts are broken away for convenience of illustration.

Fig. 4 is a perspective view of portion of the locking plate showing the converging

sides by which the plate may be locked to the reinforcement, and also showing the bottom edges of the locking plate as flared to facilitate the entrance of the reinforcement. 60

Fig. 5 shows the locking plate and reinforcement held together by means of catches comprising projections on one element engaging recesses in the other. A portion of a binding tape is shown locked in position. 65

The invention may be applied to a file which includes a cover 2 having a central crease 3 and side creases 4 and 5. Hingeably attached to the cover 2 are opposite leaves or wings 6 and 7, the leaf 6 being adjacent the side crease 4 and the leaf 7 adjacent the side crease 5. Carried by the leaf 6 and preferably passing through slits 8 therein is a flexible metal binding tape 9 having ends 10 and 11 upon which the correspondence or other paper to be filed is threaded. 70

Riveted by rivets 15 or otherwise suitably secured to the opposite leaf 7 is a metal reinforcement 12 which is preferably in one piece and U-shaped in section in order to encompass each side of the leaf 7. If desired the reinforcement 12 may be in two sections, one being placed on each side of the leaf or only one section may be employed 75 on whichever side of the leaf is deemed advisable.

Formed in the reinforcement 12 and also in the leaf 7 are incuts 13 having recesses 14 to accommodate the ends of the flexible metal binding tape 9. The recesses 14 may extend inwardly from the incuts 13 as illustrated or outwardly therefrom or in both directions as may be desired. 80

Pivoted at 17 to the metal reinforcement 95 12 or to the leaf or wing 7 is a locking plate or member 16. This locking plate is also preferably U-shaped in section. The sides or legs of the locking plate 16 may if desired, converge as shown in Fig. 4 in order 100 to facilitate the entrance of the metal reinforcement 12 between the legs of the plate 16. A portion of one of the legs of the locking plate is removed as at 18 to form an elongated opening which allows 105 the inner side of the locking plate to clear the binding tape 9. If desired the extremities of the converging ends of the legs of the plate 16 may be slightly flared as at 19 in order to facilitate the entrance of the 110 metal reinforcement 12 between the legs of the locking plate. 105

Catches of any suitable or convenient form may be employed to more effectively retain the locking plate 16 upon the reinforcement. These catches may consist of projections 20 5 jutting outwardly from the reinforcement. These projections are adapted to engage recesses 21 in the locking plate or the projections may be formed on the locking plate and engage recesses in the reinforcement.

10 The invention is used as follows:—The covers 2 are opened and the ends 10 and 11 of the flexible metal binding tape 9 bent approximately at right angles to the leaf 6. The correspondence is then threaded onto 15 the metal binding tape. The leaves 6 and 7 are next hinged upwardly into a parallel position approximately at right angles to the cover 2. The ends of the tape 9 are then passed into the respective incuts 13 and recesses 14 and are then turned either inwardly or outwardly dependent upon the position of the recesses, down upon the reinforcement 12. The locking plate 16 is finally engaged with the reinforcement 12 20 and sprung into position.

25 The papers and the binding tape are thereby securely held in position. If a paper is to be removed or fresh matter placed upon the file the operation is reversed, the fresh matter added and the file again operated as described.

Having now described my invention what I claim as new and desire to secure by Letters Patent is:—

30 1. A file for correspondence and the like comprising a cover having opposite leaves or wings, a binding tape attached to one leaf, and a metal reinforcement attached to the other leaf and having incuts therein to receive the binding tape, in combination with a substantially U-shaped locking plate pivoted at one end thereof to one of the leaves for swinging movement into position to straddle the reinforcement and lock the 35 ends of the binding tape in position.

40 2. A file for correspondence and the like comprising a cover having opposite leaves or wings, a binding tape attached to one leaf, and a metal reinforcement attached to the other leaf and having incuts therein to receive the binding tape, in combination with a substantially U-shaped locking plate pivoted at one end thereof to the reinforcement for swinging movement into position 45 to straddle the reinforcement and lock the ends of the binding tape in position.

50 3. A file for correspondence and the like comprising a cover having opposite leaves or wings, a binding tape, and a metal reinforcement having incuts therein to receive the binding tape, in combination with a

substantially U-shaped locking plate pivotally secured at one end to one of the leaves, said locking plate having converging sides or legs adapted to engage the reinforcement 65 and lock the ends of the binding tape in position.

4. A file for correspondence and the like comprising a cover having opposite leaves or wings, a binding tape, and a metal reinforcement having incuts therein to receive the binding tape, in combination with a substantially U-shaped locking plate pivotally secured at one end to one of the leaves, said locking plate having converging sides or 75 legs adapted to engage the reinforcement and lock the ends of the binding tape in position, said sides or legs having flared edges to facilitate the entrance of the reinforcement.

5. A file for correspondence and the like comprising a cover having opposite leaves or wings, a binding tape, and a metal reinforcement having incuts therein to receive the binding tape, in combination with a substantially U-shaped locking plate pivotally secured at one end to one of the leaves, said locking plate being adapted to engage the reinforcement and lock the ends of the binding tape in position, and said reinforcement 85 having catches to fasten the locking plate to the reinforcement when engaged therewith.

6. A file for correspondence and the like comprising a cover having opposite leaves or wings, a binding tape, and a metal reinforcement having incuts therein to receive the binding tape, in combination with a substantially U-shaped locking plate pivotally secured at one end to one of the leaves, said locking plate being adapted to engage the reinforcement and lock the ends of the binding tape in position, said locking plate and reinforcement constituting companion elements, one of which has catches whereby the locking plate is fastened to the reinforcement 100 when engaged therewith.

7. A file for correspondence and the like comprising a cover having opposite leaves or wings, binding tape and a metal reinforcement having incuts therein to receive the binding tape, in combination with a substantially U-shaped locking plate pivotally secured at one end to one of the leaves, said locking plate being adapted to engage the reinforcement and lock the ends of the binding tape in position, said reinforcement and said locking plate being provided with co-operating means which interengage and fasten the two elements together.

In testimony whereof I affix my signature. 120

ERNEST JACOBSEN.
